United States Patent Office

Des. 194,685
Patented Feb. 26, 1963

194,685

COMBINED BENCH, VANITY DESK AND CHEST UNIT

Merton L. Gershun, Miami Beach, Fla., assignor to American Furniture Co., Inc., Martinsville, Va., a corporation of Virginia

Filed May 24, 1961, Ser. No. 65,329

Term of patent 7 years

(Cl. D33—7)

Fig. 1.

Fig. 2.

Fig. 3.

Fig. 4.

FIGURE 1 is a perspective view of a combined bench, vanity desk and chest unit embodying my new design;

I claim:

The ornamental design for a combined bench, vanity desk and chest unit, substantially as shown and described.
